UNITED STATES PATENT OFFICE

147,714

DESIGN FOR A TOY BANK

Arthur W. Arnemann, Chicago, Ill.

Application December 30, 1946, Serial No. 135,842

Term of patent 3½ years

(Cl. D34—11)

To all whom it may concern:

Be it known that I, Arthur W. Arnemann, a citizen of the United States, residing at Chicago, in the county of Cook and State of Illinois, have invented a new, original, and ornamental Design for Toy Banks, of which the following is a specification, reference being had to the accompanying drawing, forming part thereof.

Fig. 1 is a front elevational view of a toy bank, showing my new design;

Fig. 2 is a top plan view;

Fig. 3 is a rear elevational view;

Fig. 4 is a view from the left-hand side of Fig. 1; and

Fig. 5 is a view from the right-hand side thereof.

I claim:

The ornamental design for a toy bank, as shown.

ARTHUR W. ARNEMANN.
